UNITED STATES PATENT OFFICE.

JOHN MAX MEYERS, OF WEST CHESTER, PENNSYLVANIA.

FLUID-PRESSURE LIFTING-JACK.

1,223,712.

Specification of Letters Patent.

Patented Apr. 24, 1917.

Application filed April 23, 1913. Serial No. 763,132.

To all whom it may concern:

Be it known that I, JOHN MAX MEYERS, a citizen of the United States, residing at West Chester, in the county of Chester and 5 State of Pennsylvania, have invented certain new and useful Improvements in Fluid-Pressure Lifting-Jacks, of which the following is a specification.

My invention relates to fluid pressure lifting jacks, and the object thereof is to provide a compact, simple and inexpensive construction of jack of this character that will be suitable as a part of an automobile equipment by reason of containing in storage 15 within the jack of a supply of compressed air or other fluid, so controlled as to adapt the jack for repeated operations until the pressure supply is exhausted.

My invention also has for a further object a provision of means by which the jack will be made effective in its application to bodies under which it is impracticable to insert the jack, and also to provide effective 25 means by which the jack can be expeditiously and securely attached to the axle of an automobile and other objects so as to prevent the occurrence of any accidental slipping of the jack from under the same.

My invention has further provision for 30 rendering safe the operation of the jack.

My invention primarily consists in the combination of a casing, with a plunger therefor, said plunger having an air-tight chamber for the storage of compressed air 35 or other fluid and having suitably controlled communication between said chamber and the plunger space of the casing, whereby the compressed fluid discharging therein will cause relative movement between the casing and the plunger to effect lifting.

My invention further consists in certain other novel features in the construction and arrangement of parts, all as hereinafter described and as specifically set forth in the 45 appended claims.

In the accompanying drawings,

Figure 1 is a longitudinal cross section taken through the jack on the line 3—3 of Fig. 3.

Fig. 2 shows a longitudinal cross section, as in Fig. 1, but showing the jack at its limit of extension, the jack being shown with a portion broken away.

Fig. 3 is a top view of the jack.

Fig. 4 is a bottom view of the base of the

jack without the base board shown in Figs. 1 and 2.

Fig. 5 is a detail showing a cross section taken through the discharge pipe and through the valve controlling eccentric at 60 right angles to the stem carrying the eccentric.

Fig. 6 is a horizontal section on the line 6—6 of Fig. 5.

Fig. 7 is a detail showing the packing of 65 the plunger element and clamping block in elevation, with a portion of the packing broken away.

Referring to the drawings, 8 indicates a cylindrical casing or shell open at one end, 70 being formed with a base flange 9 of rectangular form which is provided with calks 9^a on the under side thereof at each corner to insure a space underneath the casing open to the air. These calks are preferably ser- 75 rated on their under surface and as shown rest upon a base 10 of wood which is secured to the base of the casing by screws or otherwise.

The bottom of the casing 8 is formed with 80 a central opening 11 therethrough and provided with a countersunk gasket 12 of rubber or other yielding material surrounding the opening, and forming a seat for an internal valve disk 13 constituting a release 85 valve, as will more fully appear hereinafter. The valve disk 13 is concaved on its under face and presents a peripheral bearing face on which is formed two annular rings 14 which find a secure seat in the yielding gasket. 90 The valve disk is cast with a cage 15 into which the valve operating stem 16 extends and is held therein by the head or button 17 in a manner to allow of a slight vertical movement of the stem. Within the casing 95 is fitted a cylindrical tank 18 preferably of a cross section substantially that of the bore of the casing, which tank while being de- signed to contain a supply of compressed air and form a plunger to the casing cyl- 100 inder, also forms preferably the movable lifting element of the jack, being cast or otherwise formed with a flanged end portion or head 19 having a raised bearing ring 20 with a knurled surface, for securely en- 105 gaging the jack with the object being lifted.

Within the outer head of the tank is a radial bore 21, shown in dotted lines, Fig. 3, and opening directly therefrom into the tank for the purpose of charging the same, 110

2
a screw threaded nozzle 22 being provided for attachment to a pump or other source of compressed air supply, the nozzle being provided with a check valve 23 of any well known form to automatically close it by the internal pressure.

For the discharge of the compressed air from the tank into the casing below the tank there is provided a main centrally located tube 24 extending from the outer head 19 of the main tank and through the lower head 25 into which heads the threaded portions of the tube are screwed. This tube is closed at the top by a screw plug 26 which is removed to insert the valve stem 16 within same, and its threaded lower end portion extends slightly below the head 25 to receive a packing disk 27 of leather or other suitable material and a circular block 28 between which and the head 25 the packing disk is firmly clamped. The block 28 is slightly smaller in diameter than the head 25, while the packing disk is much larger, being designed to have a peripheral portion turned down against the clamping block. In order that the compressed air admitted to the casing below the tank will act of itself to evenly press the packing against the casing walls a series of grooves 29 have been formed around the periphery of the clamping block with intersecting connecting grooves 30 in staggered arrangement, so that the compressed air will be communicated uniformly throughout the grooves to create an equal pressure on all parts of the inner surface of the packing to force the same against the casing.

In the upper threaded part of the tube 24 is a side port 31 which registers with a radial passage or bore 32 made in the head 19 to its periphery, which bore is intersected by a vertical bore 33 made through the head, thus forming a passage from the interior of the tank to this central tube 24. The bore 33 receives a threaded valve tube 34 extending within the interior of the tank and inserted through the head, the bore opening therein being closed by a screw plug. The opening through the valve tube 34 is increased in diameter to form a valve recess for the ball 35 and seating spring 36 confined therein by a perforated screw plug 37. Extending up into the tube 34 into contact with the ball 35 is a push pin 38, with flattened sides. Within the end of the radial bore 32 is a screw threaded stuffing box bearing 39 for a rotary stem 40 located within the bore and carrying an eccentric 41 for depressing the pin 38 by cam action 42 on the end of said pin when the stem is partially rotated by the handle 42. As shown in the several figures of the drawing this handle is in its raised position with the eccentric depressing the push pin to its limit of movement, thus opening the ball valve

and allowing the tank to discharge compressed air through the valve tube along the flattened sides of the pin, into the recess occupied by the eccentric and from thence to the central tube 24, which will cause the raising of the tank or plunger portion of the jack. To relieve the pressure gradually and allow the tank portion to descend to its normal position on the annular support 43, the rotary stem 40 is formed with a passage 44 extending through the same, which passage is closed by the ball 45 under the seating action of the spring 46 and the pressure agent. The ball may be readily held away from its seat by the push button 47 which carries a pin 48 extending within the valve outlet. This button has a guiding extension or stop rod 49 working through the lug 50 of the handle, which prevents the button from being operated by reason of the engagement of the end of said extension or rod with the tank, as at 51, but when the handle is down or in the closed position the action is such as to bring said extension above the tank, free of engagement therewith, and thus permitting the operation of the push button only when the compressed air of the tank has been turned off and thereby preventing any opening of the release valve while the compressed air is discharging.

In order to automatically cut off the supply of compressed air to the interior of the casing, thus preventing an over expenditure of the pressure fluid, the valve stem 16 is provided with a conical head 52 which works within the enlarged portion of the bore of the tube 24 and rests within the conical seat 53 when the jack has reached its proper limit of extension, as shown in Fig. 2, but in the event that the pressure is carelessly or suddenly introduced or the jack should be accidentally relieved of its load, the expansion of the fluid will in raising the tank element beyond the point illustrated cause the valve stem 16 to lift the valve 13, thereby yieldingly retarding any explosive action and permitting the escape of the compressed air from below the tank plunger. This latter valve is initially seated by the compressing action of the coil spring 54 against the clamping block 28, so that when the compressed air is introduced it will not escape and lift the valve.

In order to adapt the jack for operation where it cannot be placed beneath the object to be raised, a chain 55 or other flexible supporting means is attached to the raising member of the jack and preferably within the slotted extension 19^a of the head 19, by a pin 56, and is designed to be looped around an object such as an axle, and caught as shown within the slot 57, which snugly receives the narrow part of the link, or it may be looped up as shown in dotted

lines with a terminal hook 58 engaging one of the links. To employ the chain for the binding of the jack securely to the object being lifted, as for instance an axle, such 5 being shown in dotted lines, the links of the chain are inserted over a stud 59 located opposite the permanent point of attachment.

I realize that considerable variation is possible in the details of construction and 10 arrangement of parts without departing from the spirit of my invention and therefore do not limit myself to the specific form shown and described.

What I claim and desire to secure by Letters Patent, is;

1. A fluid pressure jack, comprising a casing, and a plunger working within said casing, said plunger having an air tight chamber for the storage of compressed air or 20 other fluid, and having controlled communication between said chamber and the plunger space of the casing.

2. A fluid pressure jack, comprising a casing, and a tank for the storage of compressed air or other fluid, telescoping within said casing, adapted to provide a bearing at its outer end, and having controlled communication with the space between said tank and the closed end of the casing.

3. A fluid pressure jack, comprising a casing, a tank for the storage of compressed air or other fluid, extending within said casing, said tank having controlled communication with the space between it and the closed end 35 of the casing, and a packing carried by said tank for sealing the space between the walls of the tank and casing.

4. A fluid pressure jack, comprising a casing, a tank for the storage of compressed air or other fluid, extending within said casing, said tank having controlled communication with the space between said tank and the closed end of the casing, and a packing carried by said tank, said tank being provided 45 beneath said packing with a series of circumferential grooves having cross connecting grooves in open relation with the compressed air space of the casing.

5. A fluid pressure jack, comprising a casing, a plunger working within said casing, one of said elements having a chamber for the storage of compressed air or other fluid and having controlled communication between said storage chamber and the plunger space of the casing, and a release valve in 55 said casing controlled by the relative movement of the plunger and casing upon reaching a predetermined point of movement.

6. A fluid pressure jack, comprising a casing and a plunger working within said casing, said plunger having a chamber for the storage of compressed air or other fluid and having communication between said storage chamber and the plunger space of the casing, and means for closing said communica- 95

tion upon the plunger reaching a predetermined point of movement with relation to the casing.

7. A fluid pressure jack, comprising a casing, a plunger working within said casing, one of said elements having a chamber for the storage of compressed air or other fluid, and having controlled communication between said storage chamber and the plunger space of the casing, and a release valve in 70 said casing having a stem adapted to be engaged by the said plunger to cause the lifting of the valve at a predetermined point of the relative movement of the plunger and casing.

8. A fluid pressure jack, comprising a casing, a plunger working within said casing, said plunger having a chamber for the storage of compressed air or other fluid, and having communication between said storage 85 chamber and the plunger space of the casing, a valve for manually controlling the discharge of the pressure fluid through said communication, and a valve for closing said communication automatically upon the relative movement of the plunger and casing 90 upon reaching a predetermined point in their movement.

9. A fluid pressure jack, comprising a casing, and a tank for the storage of compressed air or other fluid, working within said casing, said tank having within the same a tubular passage extending longitudinally thereof and having one end in open relation to the interior of the casing, a bore 95 connecting said tube with the interior of the tank, a valve in said bore, and means for operating said valve.

10. A fluid pressure jack, comprising a casing, and a tank for the storage of compressed air or other fluid, working within said casing, said tank having within the same a tubular passage extending longitudinally thereof and having one end in open relation to the interior of the casing, a bore 105 connecting said tube with the interior of the tank, a valve in said bore, and a rotary stem 110 carrying an eccentric for operating said valve.

11. A fluid pressure jack, comprising a 115 casing, and a tank for the storage of compressed air or other fluid, working within said casing, said tank having within the same a tubular passage extending longitudinally thereof and having one end in open 120 relation to the interior of the casing, a valve controlling the discharge of the pressure agent into said passage, a rotary stem having an eccentric for operating said valve, and a push pin interposed between said valve and 125 said eccentric.

12. A fluid pressure jack, comprising a casing, and a tank for the storage of compressed air or other fluid, working within said casing, said tank having within the 130

- same a passage connecting said tank with the interior of the casing, a valve controlling the discharge of the pressure agent into said passage, a rotary stem having an eccentric 5 for operating said valve, and a valved release passage through said stem.
13. A fluid pressure jack, comprising a casing, and a tank for the storage of compressed air or other fluid, working within 10 said casing, said tank having communication with the interior of the casing and beneath the tank, a valve normally closing said communication, means for opening said valve, a release passage for conducting the compressed air from the casing, a normally closed valve 15 in said passage, and means for opening said latter valve, said means being adapted to lock against operating when the first-mentioned valve is in open position.
14. A fluid pressure jack, comprising a casing, and a tank for the storage of compressed air or other fluid, working within 20 said casing, said tank having communication with the interior of the casing beneath the tank, a valve normally closing said communication, means for opening said valve, a release passage for conducting the compressed air from the casing, a normally closed valve 25 in said passage, and an operating push button therefor locked against operation by the opening of the valve controlling the discharge from said tank.
15. A fluid pressure jack, comprising a casing, and a tank for the storage of compressed air or other fluid, working within 30 said casing, said tank having communication with the interior of the casing beneath the tank, a valve normally closing said communication, a rotary stem for opening said 35 valve, a release passage for conducting the compressed air from the casing, a normally closed valve in said passage, and an operating push button therefor carried by the 40 said rotary stem and having a stop adapted 45 to engage the tank when the said stem is in the open position.
16. A fluid pressure jack, comprising a casing, and a tank for the storage of compressed air or other fluid, working within 50 said casing, said tank having within the same a tubular passage extending longitudinally thereof and having one end in open relation to the interior of the casing, and the said casing having a stem extending within the said passage and having a valve adapted 55 to seat within the same at a predetermined point of the raising movement of the tank.
17. A fluid pressure jack, comprising a casing, and a tank for the storage of compressed air or other fluid, working within 60 said casing, said tank having within the same a tubular passage extending longitudinally thereof and having one end in open relation to the interior of the casing, and the said casing having a valve in its base, a 65 stem connected to said valve, extending within the said tubular passage and adapted to be engaged at a predetermined point of the raising movement of the tank to operate said valve and release the compressed air from 70 the casing.
18. A fluid pressure jack, comprising a casing, and a tank for the storage of compressed air or other fluid, working within 75 said casing, said tank having within the same a tubular passage extending longitudinally thereof and having one end in open relation to the interior of the casing, and the said casing having a valve in its base, a stem connected to said valve having a vertical 80 play independent of the valve, said stem extending within the said tubular passage and carrying a valve adapted to seat therein at a predetermined point of the raising movement of the tank.

In testimony whereof I affix my signature
in presence of two witnesses.

JOHN MAX MEYERS.
